UNITED STATES PATENT OFFICE.

LOUIS STEINBERGER, OF NEW YORK, N. Y.

TELEPHONE-STAND.

No. 859,702.

Specification of Letters Patent.

Patented July 9, 1907.

Application filed February 8, 1905. Serial No. 244,729.

To all whom it may concern:

Be it known that I, LOUIS STEINBERGER, a citizen of the United States, and a resident of the city of New York, borough of Brooklyn, in the county of Kings and State of New York, have invented a new and Improved Telephone-Stand, of which the following is a full, clear, and exact description.

My invention relates to telephone stands and fixtures applicable to such stands for the purpose of enabling the stands to perform duties relating in various degrees to telephony or to work incidental thereto.

Reference is to be had to the accompanying drawings forming a part of this specification, in which similar characters of reference indicate corresponding parts in all the figures.

Figure 1 is a perspective view showing a telephone stand equipped with my invention; Fig. 2 is a fragmentary vertical section through the base of the same; Fig. 3 is a fragmentary elevation of the base and the accompanying fixtures viewed as from the right of Fig. 2; and Fig. 4 is a detail perspective view showing one of the twin supporting plates constituting a shelf used for certain purposes hereinafter described.

A vertical stem 5 is provided with a transmitter casting 6 and with a switch hook 7, the latter being used for supporting a receiver 8. The stem 5 is connected with a pedestal 9 by any appropriate means, being preferably threaded and screwed into the base, as indicated in Fig. 2.

A pair of semicircular plates 17 are each provided with a rim 18 having the form of a bead projecting upwardly therefrom as indicated in Fig. 4. Each of these plates is further provided with a semicylindrical bearing 19 provided with ears 20, these ears having oppositely disposed holes 21 as will be understood from Figs. 1 and 4. One of the plates 17 is provided with a section 22 upon which is printed or otherwise placed a number of telephone calls, and with another section 23 having a silicate or slate surface upon which memos may be written and from which it may be erased at will. The supporting rims 18 prevent articles from rolling off, and the twin plates therefore may be considered as constituting a two-part annular table which may be used for the general purpose of retaining articles placed temporarily thereupon. The twin plates are held together by means of screw bolts 24 which clamp together the oppositely disposed ears 20 and thus hold the semicylindrical bearings 19 in registry with each other as will be understood from Fig. 1. As the tension of the bolts 24 may be adjusted at will, the pressure of the cylindrical bearings 19 may be correspondingly regulated, and the circular table formed by

the semicircular plates 17 is therefore adjustable to any desired height; moreover, the table may be rendered revolvable when the parts are disposed as indicated in Figs. 1, 2 and 3.

Mounted upon the underside of the twin plates 17 is a leg 25 connected to the plate by means of a screw 26 which engages a flange 27 integral with the leg. At the bottom of each leg 25 is a foot 28 having the same curvature as the pedestal 9. It will be noted that about one-half of each flange 27 projects from the edge of its plate as will be seen from Fig. 4. This flange holds the adjoining edges of the two plates 17 in exact registry with each other, so that the two-part table is perfectly level and presents a smooth upper surface.

One of the principal uses of the table is to serve as a rest for the telephone receiver 8. This enables the operator to step away from the telephone without replacing the receiver on the switch hook. It also enables the operator to employ both hands as an aid to looking up records or the like.

I do not limit myself to any particular materials out of which any of the parts above described are made, nor to the exact shape or conformity of any of these parts as shown.

Having thus described my invention, I claim as new and desire to secure by Letters Patent:

1. In a telephone stand, the combination of a stem, a transmitter supported thereby, a table connected directly with said stem and made up of oppositely disposed twin members in registry with each other, and means for clamping said twin members together.

2. A telephone stand, comprising a stem and a pair of oppositely disposed twin plates, each of substantially semicircular form and provided at its outer edge with a rim having the form of a raised bead, said twin plates being further provided with bearing portions mating each other, and means for clamping said bearing portions upon said stem.

3. A telephone stand, comprising a stem, a pedestal for supporting the same, a pair of twin plates mating each other and mounted upon opposite sides of said stem, means for securing said plates together, and a leg mounted upon each of said twin members for the purpose of engaging said pedestal.

4. A telephone stand, comprising a supporting stem, a pedestal therefor, and a circular table made in two semicircular parts in alinement with each other, each of said parts having a leg provided with a foot for engaging said pedestal, and also having a surface for partially encircling said stem.

5. A telephone stand, comprising a stem, a pedestal therefor, a pair of arcuate members mating each other and mounted upon opposite sides of said stem and bolted together, a plate mounted upon each of said supporting members and provided with a leg, said leg of one plate having a portion projecting from it so as to overlap the other plate.

6. A telephone stand, comprising a supporting stem, a

pedestal for supporting the same, and a circular table made in two semi-circular parts bolted together, and provided with twin surfaces for engaging said stem, each of said semi-circular parts having a leg provided with a

5. foot for engaging said pedestal.

7. A telephone stand, comprising a stem, a telephone transmitter mounted thereupon and adjustable relatively thereto, a table provided centrally with an aperture enclosing said stem whereby opposite halves of said table are

disposed upon opposite sides of said stem, and supporting 10 members mounted upon opposite sides of said table and adapted to engage a pedestal.

In testimony whereof I have signed my name to this specification in the presence of two subscribing witnesses.

LOUIS STEINBERGER.
